UNITED STATES PATENT OFFICE

IRVING GOLDBURG, OF SUFFERN, NEW YORK

SHADE APPARATUS

Application filed May 21, 1930. Serial No. 454,359.

This invention relates to improvements in means of attachment for window shades, awnings, and the like to their supporting rollers, and has as its essential object simple, inexpensive, and effective detachable anchorage of the shade to the roller.

A further object is the provision of such means of detachable anchorage while affording substantial uniformity in smoothness of the rolled shade, which, considered negatively, includes the avoidance of appreciable lateral projections at the places of anchorage.

With these and other objects in view as will in part hereinafter become apparent and in part be stated, the invention contemplates direct and effective anchorage in the material of the roller by which a shade is adapted to be easily, quickly, and inexpensively detachably mounted so that replacement can be effected with facility.

The invention also comprises certain other novel constructions, combinations, and arrangements of parts as subsequently specified and claimed.

25 In the accompanying drawings,—

Figure 1 is a view in side elevation of a shade and its roller and the connecting means therefor incorporating an embodiment of the present invention, parts being broken away and one of the attaching means being seen in the condition of application of the shade.

30 Figure 2 is a transverse section in the plane of one of the fasteners, the fastener being seen in elevation, and the retaining prongs of the fastener being shown in dotted lines in the condition of application of the shade.

Figure 3 is a perspective view of one of the fasteners detached.

35 Figure 4 is an inverted plan view of a modified embodiment of fastener detached.

Figure 5 is a sectional view of the detached fastener taken on the plane indicated by line 5—5 of Figure 4.

40 Figure 6 is a view similar to Figure 5 of a detached fastener incorporating a modified embodiment.

Figure 7 is an inverted plan of the parts seen in Figure 6.

45 Figure 8 is a side elevation of a further modified embodiment of fastener detached.

Figures 9 and 10 are views similar respectively to Figures 6 and 7 of a still further modified embodiment of fastener.

Figure 11 is a fragmentary, transverse section through a roller and shade having applied thereto a still further modified embodiment of fastener.

Figure 12 is a perspective view of the form of fastener seen in Figure 11.

Figure 13 is a perspective view of another modified embodiment of fastener.

Figures 14, 15, 16, and 17 are detailed, fragmentary plan views of parts of shades illustrating various forms of openings adapted to cooperate with the fasteners or attaching means.

Figure 18 is a perspective view of a modified embodiment of fastener.

It has heretofore been proposed to detachably connect a shade to a roller by expensive and unsatisfactory expedients, including either the grooving or other special shaping of the roller and the employment of encircling spring clamps or the provision of detachable attaching means cooperating with a permanently attached strip. Among the various objects of the present invention is the detachable anchorage of a shade to a roller by means penetrating the material of the roller and directly engaging the shade without requiring any special grooving or other shaping of the roller and without interposition of any permanently attached strip. Numerous detailed means may be employed for accomplishing this result, some of the successful forms of which are illustrated in the accompanying drawings.

Referring to the drawings by numerals, 1 indicates an ordinary, conventional roller which is indicated as a window shade roller, but may be any appropriate shade roller, such as employed for awnings, and the like. Mounted on the roller 1 is the shade 2 which, while shown as a window shade roller, may be any other appropriate shade including awnings and like shade devices.

The roller-engaging end of the shade 2 is provided with a series of apertures 3 aligned adjacent the free margin of the shade end. For each aperture 3 a fastener, as seen in de-

tail in Figure 3, is employed consisting essentially of a center part or body 4 from which projects the roller-engaging prongs 5, 5, and the shade-engaging prongs 6, 6. The 5 prongs 5 are preferably formed with pointed, inner ends for enabling easy penetration of the wood or other material of roller 1, and, in order to insure effective anchorage while using comparatively short prongs 5, the free 10 ends of the prongs 5 are preferably shoulered to produce arrow heads 7, 7. Thus, when the prongs are forced into the material of the roller 1, the shoulders of the arrow heads 7 will resist withdrawal owing to the 15 spring of the wood fiber across the shoulders of the arrow heads as the latter enter the material of the roller. Hence, it is practicable to employ comparatively short prongs 5 while affording dependable anchorage, and this is 20 especially desirable in that type of roller hollowed out to contain an operating spring as is common practice with shade rollers.

In applying the fastener after the prongs 5 have been forced into the material of the roller 1 to the required extent, the prongs 6 are 25 bent to an outstanding position, as seen in full lines at the lefthand end of the roller in Figure 2. Obviously, as many of the fasteners are applied to the roller 1 as required and 30 their prongs 6 bent to the outstanding position, and then the shade 2 is applied, an aperture 3 having been previously formed in the shade for each of the fasteners. As soon as 35 the shade has been applied, the prongs 6 are straightened down upon the shade into the position seen at the righthand end portion of Figure 1. The shade and roller are then in condition for regular use.

Obviously, when it becomes desirable to 40 replace a used shade with a new one, it is only necessary to bend the prongs 6 of the several fasteners to the outstanding position, withdraw the old shade, apply the new one, and bend the prongs back to the outstanding 45 position.

The resulting combination of parts is especially effective for facilitating easy and inexpensive repair, alteration, or modification. For instance, if light shades are desired during the winter and dark shades during the summer, the interchange can be made without the provision of new rollers or the tedious and trying task of removing permanent fasteners and refastening. In addition 50 to the actual labor of removing permanent fasteners, the question of effective alinement sometimes occasions difficulty, especially when the shade is changed by an inexperienced hand. With the present invention the 55 fasteners would ordinarily be supplied on the shade rollers ready for use, and the operator would have only the simple task of buttoning the shade to the roller.

In Figures 4 and 5 a modified form of fastener is illustrated in which the buttoning

operation is accomplished without variation in the actual location of any part of the fastener. In this structure a collar or sleeve 8 is provided and carries an outstanding, button-like flange 9. Prongs 10 project edge-wise from the collar 8 and function the same as prongs 5 of the above-described fastener. When the fastener of Figures 4 and 5 is employed, the prongs 10 are forced into the material of the roller until the inner edge of collar 8 strikes the roller, and the fastener is then in condition for use. When this particular fastener is employed, or similarly shaped fasteners, the shade, as seen in Figure 17, is preferably provided with a key-hole opening or slot 11 for each fastener, the enlarged portion of each slot being substantially of the diameter of the button head or flange 9 so that the shade can be easily dropped over the button and drawn lengthwise until the collar 8 is located in the elongated portion of the key-hole slot. Obviously, the opening in the shade may be otherwise formed, as, for example, it may be a slot 12, as seen in Figure 16, simulating a button-hole. In that instance, the shade would literally be buttoned over the several fasteners and the collars 8 would extend through the slots 12 while the flanges 9 would lie outside of the shade. The collar 8 is preferably comparatively short, being of a length substantially equal to the thickness of the shade to be applied or may be of a length equal to double that thickness in case a return fold 95 of the shade is employed.

In Figures 6 and 7 is illustrated a further embodiment in which a collar 13 is provided with the button flange 14 and is adapted to be secured to a shade roller by a tack or pin 15 having a head overlying the flange 14, and 100 a shank extending through the collar and into the material of the roller.

In Figure 8 is illustrated a further modified embodiment in which a button head 16 is formed integral with a short shank 17 terminating in an extended reduced shank 18, the short shank providing a stop shoulder, and the shank 18 being adapted to be driven into the material of the roller to a position with the inner end of the shank 17 110 abutting against the surface of the roller. The operation of the parts of the structures seen in Figures 6 and 7 is the same, after anchorage to the shade roller, as described above with respect to the fastener of Figures 4 and 5.

In Figures 9 and 10 is illustrated a further embodiment in which a collar 19 is provided and a tack or pin 20 has its shank extending through the collar and through a turn-button 21, so that the head of the pin 20 retains the turn-button 21 in engagement with the collar. The tack or pin 20 is driven into the material of the roller until the inner edge of collar 19 is seated against the roller, 125

- and then the turn-button 21 is preferably engaged by the shade by having the shade provided with slots 12 located to accommodate passage of the turn-button therethrough.
- 5 After the turn-button has passed through the respective slot in each instance, the turn-button is turned at right angles so as to extend crosswise of the slot and thus effectively anchor the shade to the roller. Obviously,
- 10 the arms of the turn-button 21 may be of sufficiently pliable material to enable the arms to be bent to an outstanding position so as to function in the manner described with respect to the prongs 6 and to accordingly cooperate with an aperture 3.
- In Figures 11, 12, and 15 is shown a further modified embodiment in which a shade roller penetrating part carries a spring prong adapted to be sprung into position for detachably retaining a shade in engagement with a roller. In this structure, 1' indicates the roller and 22 the shank of the fastener, which shank may be constructed in any appropriate manner to provide effective anchorage in the roller, the form shown including the provision of screw threads for the shank 22. When the shank 22 is a screw, its head 23 is provided with the usual kerf and preferably formed integral with the head is a laterally-extending spring prong 24 bent to have its free end portion normally lie against the surface of the roller 1' when the fastener has its shank seated in the material of the roller. The said free end portion of prong 24 is preferably out-turned, as at 25, insufficiently to outstand as far as the balance of the structure but sufficiently to facilitate introduction of material between the free end of the prong and the roller. When employing this type of fastener, the shade 2' may be provided with an aperture similar to aperture 3, but is preferably formed with an aperture having a grommet or eyelet 3' to stabilize the connection between the shade and the fastener, and, in the event of the use of such eyelet, the eyelet is curved bodily to correspond to the curvature of the surface of the roller, as clearly seen in Figure 11. In the operation of the structure as seen in Figures 11, 12, and 15, the shade is applied by having the several eyelets 3' introduced beneath the free ends 25 of prongs 24 and the parts drawn up until the eyelets surround the respective heads 23. The prong 24 in each instance is proportioned to afford a sufficient space between the free end of the prong which contacts with the roller 1' and the place of connection of the prong with the head of the shank to accommodate an appropriate portion of the shade. Thus, when the parts have been assembled, the head 23 will resist tendency of the shade to escape from its engagement incident to sudden retrograde movement, and the free end portion of the prong 24 will effectively resist such tendency.

The spring prong type of fastener is susceptible of quite a wide range of variations, two additional forms being illustrated, respectively, in Figures 13 and 18, in which the roller penetrating parts are driven prongs 70 rather than screw-threaded. In Figure 13, the shanks 22' are duplicated to produce a staple 23' having a laterally-extending spring prong 24' terminating at 25' in an outstanding portion adapted to accommodate passage 75 of a shade to position while the prong has its free end portion tending to rest against the roller.

In Figure 18, the structure is quite similar to that seen in Figure 13, except that the parts 80 are formed from sheet material instead of a bent rod. The shanks 22'' are carried by the body 23'' and the body is formed with the spring prong 24'' having the terminus 25''. The operation of the fasteners of Figures 13 85 and 18 will be substantially the same as that described with respect to Figure 11, except that the eyelet 3' is ordinarily preferably not employed, and the opening in the shade utilized therefore preferably corresponds with 90 the opening 3 so that portions of the material of the shade overlie parts of the body of the fastener.

What I claim is:—

1. The combination, with a shade roller, 95 of a fastener permanently anchored to the roller for detachably attaching a shade, such fastener comprising a body outstanding from the roller, a prong extending from the body into the material of the roller and anchored 100 therein and having means of resisting withdrawal therefrom, and a prong exposed beyond the roller and located to removably overhang a shade engaging the outstanding body.

2. The combination, with a shade roller, of 105 a fastener permanently anchored to the roller for detachably attaching a shade, such fastener comprising a body outstanding from the roller, a prong extending from the body into the material of the roller and anchored 110 therein and having means of resisting withdrawal therefrom, and a prong exposed beyond the roller and located to removably overhang a shade engaging the outstanding body, the prong being bendable to be moved to and 115 from a position facilitating buttoning a shade over said body.

3. The combination, with a shade roller, of 120 a fastener permanently anchored to the roller for detachably attaching a shade, said fastener comprising a spacer outstanding from the surface of the roller, a prong extending from the spacer into the material of the shade roller to provide permanent anchorage thereto, and means for detachably retaining a 125 shade in engagement with said spacer.

In testimony whereof I affix my signature.
IRVING GOLDBURG.
